UNITED STATES PATENT OFFICE.

THEODORE H. ALCORN, OF KANSAS CITY, AND EARL L. CHATFIELD, OF MOUNT WASHINGTON, MISSOURI.

RUBBER-DISK ATTACHER FOR BOTTLE-STOPPERS.

SPECIFICATION forming part of Letters Patent No. 728,351, dated May 19, 1903.

Application filed July 19, 1902. Serial No. 116,298. (No model.)

To all whom it may concern:

Be it known that we, THEODORE H. ALCORN, residing at Kansas City, and EARL L. CHATFIELD, residing at Mount Washington, in the 5 county of Jackson and State of Missouri, citizens of the United States, have invented certain new and useful Improvements in Rubber-Disk Attachers for Bottle-Stoppers, of which the following is a specification.

- 10 This invention relates to rubber-disk attachers for bottle-stoppers; and our object is to produce means for disposing the disks in place easily and quickly without injuring them.
- 15 To this end the invention consists in certain novel and peculiar features of construction and combinations of parts, as hereinafter described and claimed, and in order that it may be fully understood reference is to be had 20 to the accompanying drawings, in which—

Figure 1 is a perspective view showing the attacher as arranged for disposing a rubber disk upon a porcelain bottle-stopper. Fig. 2 is a horizontal section of the same. Fig. 3 is a 25 vertical section of the same. Fig. 4 is an inverted plan view of part of the split barrel-clamp.

Referring now to the drawings in detail, 1 designates a base-plate, preferably of cast 30 metal and provided with an arm 2. In practice the plate is preferably secured to an upright with its arm projecting horizontally; but it may be secured upon a table with said arm projecting vertically upward. In opposite sides of the arm near the base are cavities 3, and extending through the outer end of the arm at right angles to said cavities is a pivot 4, upon which is mounted the members 5 of a clamp, the jaws of the clamp being 35 semicylindrical in cross-section in order to form a tube or barrel when closed. The bore of this tube or barrel is by preference conical, as shown at 6, and is formed at one side (its lower side when arranged horizontally) with 40 a slot 8, formed by cutting away the edges of the jaws, as at 7, the object of this slot being to enable the spreader, hereinafter referred to, to be more readily dislodged when necessary. The bore is sharply choked at its front 45 end, as at 8^a, to insure close connection with

the spreader at that point, and thus guard against the disk, hereinafter mentioned, wholly or partially entering the barrel-clamp with the spreader.

9 designates a pair of coil-springs which engage the cavities 3 at their inner ends and at their outer ends sockets 10 of the handle ends of the clamp and tend to hold the jaws of the latter together.

11 designates a pair of intersecting levers 60 pivoted to boss 12 of plate 1 and constituting a pair of pincers, the jaws 13 of the same being provided with recesses 14 to engage the outer sides of the handle ends of the clamp members. The handle ends of the 65 pincers are connected by a cord or other flexible connection 15, and this is connected in turn by a cord 16 with a foot-lever or treadle 17, pivoted to work vertically in a bracket 18, secured to a wall or other support, the 70 arrangement being such that foot-pressure on the lever or treadle operates the pincers against the resistance of springs 9 and opens the jaws to enable the spreader, presently described, to drop or be drawn out of the clamp. 75 It drops out through slot 8 when the clamp occupies a horizontal position and is withdrawn when the clamp is arranged vertically.

The spreader 19 is of conical form and dished at its base, as at 20, and is forced 80 partly through the rubber disk, as at 21, the latter being first lubricated for easy movement on the spreader by being dipped in water. The spreader is then forced into the barrel-clamp until the disk comes in contact 85 with the end of the barrel, as shown in Fig. 1.

When it is desired to equip a porcelain stopper, as at 22, with a rubber disk, the attenuated end of said stopper beyond and of greater diameter than the grooved portion 23 is fitted 90 in the dished end of the spreader, and then sufficient pressure is brought to bear upon the stopper to force the spreader into the clamp until the rubber disk registers with and snaps into the groove of the stopper, this action being rendered positive and reliable because the close fit between the spreader and choked end of the barrel prevents the disk from getting pinched between them, and consequently invariably effects its proper deposit 95 100.

on the stopper. Immediately after this takes place the equipped stopper is thrown aside, and by depressing the lever or treadle, and thereby throwing the jaws apart, the spreader 5 is permitted to drop down through slot 8 into the operator's hand or upon the workbench.

In Fig. 3 is shown an ordinary wire stopper 24, the same being provided with a head 25 at one end and a smaller enlargement 26 a 10 slight distance from said head, so as to provide a space between them to receive a rubber disk. With this type of stopper, it is preferable to use a spreader, as at 27, provided with a slot 28 and a hole 29, leading from its 15 base to said slot, the base being of course dished or concaved, as hereinbefore explained. Upon this spreader the disk is placed in the manner already explained, and then the spreader is inserted in the clamp. The free 20 end of the wire stopper is then slipped through the hole 29 in the base and through the registering slots 28 and 8 or, if no slot 8 is provided, through the space between the jaws, as the latter will be forced apart some distance 25 by the insertion of the spreader. The stopper is then manipulated in such a manner that the enlargement 26 fits snugly in the dished portion or cavity 20 of the spreader, as shown by dotted lines in Fig. 3. The operator 30 then by means of the butt-end of an awl or other equivalent tool forces the spreader inwardly between the jaws until the disk is forced beyond the end of the spreader and snaps upon the wire stopper between its head 35 25 and enlargement 26. The spreader may then be withdrawn by pulling outward on the stopper, or the stopper may be first withdrawn and the spreader withdrawn by slipping the small end of the tool through the slot 28, or 40 it may be removed by opening the clamp in the manner previously described.

The above-described manner of equipping the wire stopper with the rubber disk is the preferred one; but it may also be equipped 45 by slipping the disk over the head 25 through the medium of a clamp and a spreader of proper proportions, as will be readily understood.

Heretofore all devices for attaching rubber 50 disks to stoppers of the types shown have usually been instruments which were inserted in the holes of the disks, stretching the latter and slipping them upon the stoppers, which operation was frequently attended by injury 55 to the disks.

By the use of our spreaders the disks can be attached to the stoppers with the danger of tearing the former practically eliminated, and such operation can also be performed 60 much more expeditiously than in the old way.

Having thus described the invention, what

we claim as new, and desire to secure by Letters Patent, is—

1. A rubber-disk attacher for bottle-stoppers, comprising a split tubular clamp, and a 65 disk-carrying spreader to be forced into said clamp until the latter pushes the disk off the end of the spreader onto the stopper.

2. A rubber-disk attacher for bottle-stoppers, comprising a split tubular clamp, and a 70 disk-carrying spreader to engage the clamp and provided with a dished or recessed base.

3. A rubber-disk attacher for bottle-stoppers, comprising a split tubular clamp, and a 75 disk-carrying spreader, provided with a slot and hole opening from said slot through its base.

4. A rubber-disk attacher for bottle-stoppers, comprising a split tubular clamp, a disk-carrying spreader to be forced into the clamp, 80 and means to move the jaws of the clamp apart to effect the extraction of the spreader.

5. A rubber-disk attacher for bottle-stoppers, comprising a split tubular clamp, composed of two members pivoted together and 85 having the inner faces of one end of said members recessed, the front end of the recesses being segmental and of smaller diameter than the body portions thereof, said recesses conjointly constituting a bore having 90 its front end choked, springs for holding the jaws pressed yieldingly toward each other, and a disk-carrying spreader, circular in cross-section, to be forced into the clamp until the ends of said jaws push the disk off the 95 end of the spreader onto the stopper.

6. A rubber-disk attacher for bottle-stoppers, comprising an arm, a tubular clamp consisting of two members pivoted together and to said arm, springs bearing at their opposite ends against said arm and the handle ends of said clamp members, pincers engaging said handle ends, and a foot-lever or treadle connected to the pincers to operate the same and thereby open the clamp. 105

7. In a rubber-disk attacher for bottle-stoppers, a split barrel-clamp having its jaws pressed yieldingly together and the bore of 110 its jaws choked or contracted at its front end.

8. In a rubber-disk attacher for bottle-stoppers, the combination of a split barrel-clamp having the front end of its bore choked or contracted, and a conical disk-carrying spreader to be forced like a wedge into said 115 split barrel-clamp.

In testimony whereof we affix our signatures in the presence of two witnesses.

THEODORE H. ALCORN.
EARL L. CHATFIELD.
